ROTARY COMPRESSOR

Cecil J. Beust, Atlanta, Ga.

Application November 21, 1933, Serial No. 699,066

17 Claims. (Cl. 230—205)

This invention which is a continuation-in-part of my application Serial No. 641,079, filed November 3, 1932, relates to rotary compressors. Its purpose is to provide means for sealing the compression chambers of such apparatus against leakage of the compressed fluid.

Compressors or pumps employing the very desirable fundamental principle of rotary motion have heretofore enjoyed but a limited field of usefulness on account of their inherent fault of slippage or short circuiting of the fluid being pumped or compressed, whereby their volumetric efficiency is low, and the inefficiency increases in direct ratio to the discharge pressure.

15 New fields have been developed for the employment of fluid pressure pumps or compressors, notably the mechanical refrigeration art, which can tolerate no compression leakage whatsoever, and from which new fields the rotary compressor is substantially barred on account of its defect of inherent compression leakage, despite its otherwise ideal mechanical qualifications.

The present invention has for its object the construction of a compressor or pump of any known type in which the chambers are hermetically sealed against leakage by pressures on the outside in excess of the pressures from within and which outside pressures are derived from pressures within.

30 A more specific object of the invention is to provide means for sealing the chambers of the rotary pump or compressor, the outside area of which means exceeds the aggregate area pressed against from within the pump or compressor and which sealing means are opposed to the within pressure responsive to fluid pressure acting upon certain localized areas on the outside of said sealing means, ordinarily greater than the areas 35 pressed upon from within, but being ordinarily less than the entire outside area of said sealing means so as to prevent the building up of excessive sealing pressures which might create undesirable or disastrous friction with respect to the 40 rotating parts of the pump or compressor.

Inasmuch as those parts of the rotor of the compressor which are subject to maximum angular velocity in the operation of the compressor would be the most susceptible to the destructive 45 friction created by excess sealing pressure against said portions of the rotor of the pump or compressor, the invention contemplates the withdrawing of the fluid pressed areas on the outside of said sealing means away from the peripheral region of said sealing means whereby the periph-

eral portions of the rotor will be relieved from the maximum value of the sealing pressure.

Another object of the invention is the provision of means for creating an initial pressure bias upon the outer side of said sealing means rendering the latter effective until sufficient pressure has been generated within the compressor or pump to supplant the initial pressure creating means.

10 A further object of the invention is to provide in a compressor of the vane type trunnions for taking the end thrust of the vanes when the ends of the latter are exposed to the high pressure at the discharge of the compressor, without transmitting the said end thrust through the rotor 15 itself and to the opposite side thereof.

Still another object of the invention in connection with the trunnions is the provision of split expansion rings seated on said trunnions, with clearance and abutting expansively against the inner ends of the vanes whereby they are constantly pressed against the peripheral wall of the pump or compressor with a resilient pressure which at all times compensates for wear.

Another object of the invention is to provide a 25 compressor in which a single rotor is arranged to draw a plurality of suction pressures of different values.

Other objects of the invention will appear as the following description of a preferred and practical embodiment of the invention proceeds.

Although there are probably a number of known types of rotary compressors or pumps to which the present invention may be applied, it has been exemplified in the accompanying drawings by illustrating it in combination with two types of compressor.

In the drawings, the same characters of reference have been used throughout the several figures to designate identical parts.

40 Figure 1 is a vertical side section, a portion of the rotor of the compressor being shown in elevation;

Figure 2 is a section taken along the line 2—2 of Figure 1;

Figure 3 is a detail taken in a plane perpendicular to the axis of rotation of the compressor illustrating the relation of the expansion ring to the trunnion and to the vanes;

Figure 4 is a section taken along the line 4—4 of Figure 3;

Figure 5 is a horizontal section through the compressor, part being omitted;

Figure 6 is a section taken along the line 6—6 of Figure 1;

Figure 7 is a detail in section taken along the line 1—7 of Figure 6;

5 Figure 8 is a perspective view of the flexible cupped members or pistons by means of which sealing pressure is applied to the sealing ring;

Figure 9 is a perspective view of the sealing ring partly in section;

Figure 10 is a section taken along the line 10—10 of Figure 9;

10 Figure 11 is a view in detail showing the unrestrained cross-sectional shape of any one of the cupped members or pistons and illustrating the manner in which it is seated within the recesses in the head.

15 Figure 12 is a view in detail showing the construction of the packing for the outer shoes of the vanes;

Figure 13 is a diagrammatic representation of the lubricant circulation;

20 Figures 14 and 15 are respectively, vertical sections through an alternative form of compressor taken in perpendicular planes;

Figure 16 is a perspective view of the sealing ring employed in that form of the invention shown

25 in Figures 14 and 15;

Figures 17 and 18 are respectively, sections taken along the lines 17—17 and 18—18 of Figure 16; and

30 Figures 19 and 20 are respectively, an exploded perspective view and a section view through a modified form of shoe construction.

Figure 21 is a detail of an alternative construction to that shown in Figure 5.

35 Referring now in detail to the several figures and first advertiring to that form of the invention shown in Figures 1 and 2, the compressor comprises a stator which includes a support 1 and a casing in general designated by the reference character 2 and comprising a generally cylindrical portion 3 and end heads 4 and 5 suitably secured to the peripheral portion. The inner wall 6 of the peripheral portion is cylindrical. A rotor 7 is mounted within the space enclosed between the peripheral portion of the casing and the heads, said rotor being mounted upon an axis 8 which is eccentric to the axis of the peripheral wall of the stator. The diameter of the rotor is such that it makes contact with the inner peripheral wall of the casing, preferably at the lower side of the compressor. In order that the region of contact between the rotor and stator may be more than a line of tangency, the inner peripheral wall of the rotor, is through an appreciable arc, machined to a curvature corresponding to that of the rotor and forming a seat for the rotor which will hereinafter be referred to as the arc of expulsion. The rotor is formed with radial slots 9 extending there-across and opening in the ends of said rotor. Sliding vanes

40 10 are mounted in the slots of said rotor extending there-across and terminating in planes flush with the ends of said rotor. At opposite ends of the rotor is formed with circular recesses 11, see Figure 4, concentric to the shaft 12 of the rotor which shaft extends through suitable bearings and finally to the exterior of the machine.

45 The heads 4 and 5 are provided with trunnions 13 and 14 which extend into the recesses in the ends of the rotor. The trunnions are concentric to the inner peripheral wall of the cylinder and therefore they are eccentric with respect to said recesses. Consequently, the latter must be made considerably larger than the diameter of the trunnions so as to encompass the trunnions freely

50 in all angular positions of the rotor. Thus, re-

5 ferring to Figure 1 the wall of the recess approaches very close to the trunnion adjacent the point 15, but extends quite a distance below said trunnion as shown at 16 in the same figure. The slots 9 which serve as guideways for the vanes open into the cylindrical walls of the recesses 11. Expansible metallic split rings 17 and 18 are mounted with clearance on the ends of the trunnions which extend within the recesses 11. Figure 4 shows that the rings 17 are split diagonally 10 widthwise as indicated at 19 in Figure 4. The lower ends of the vanes are provided with a concave semi-cylindrical seat 20 extending there-across and within said seat a shoe is freely mounted, said shoe having a convex surface matching 15 the concave seat. The working faces of the shoes 21 are concave and the split rings 17 and 18 are expanded outwardly against said shoes, keeping the vanes in intimate contact with the inner peripheral wall of the stator.

20 On account of the clearance between the split rings and the trunnions, and the frictional pressure of the rings against the vanes, the rings are held relatively immovable, revolving with the rotor about the trunnions. The vanes do have an 25 inevitable slight relative motion with respect to the surfaces of the split rings, since the eccentricity of the rotor causes a relative displacement of the bottoms of the vanes against the split rings through an amplitude equal to twice the 30 eccentricity of the rotor. The ring therefore acts not only as a wear compensating means for the vanes, but also as a wear piece to minimize the wear between the shoes 21 and the ring itself. The primary function of the ring and trunnion 35 construction however is to afford a rigid abutment for receiving the end thrust due to the pressure of the compressed fluid against the ends of the vanes when the latter become exposed during their period of transit across the discharge 40 port, best shown in Figure 2. In the absence of some fixed abutment such as the trunnions, such end thrust reacts against the rings forcing the rings themselves toward the diametrical opposite side of the stator and pushing the ends of the 45 opposite vanes against the inner peripheral wall of the casing with excessive and destructive pressure.

The upper ends of the vanes are provided with shoe pieces 23 similar to the shoes at the inner 50 ends of the vanes excepting that their working faces are convex corresponding to the curvature of the inner peripheral wall of the casing.

Figure 2 shows that there is a suction port 24 opening at a point 25 adjacent one end of the 55 arc of expulsion and circumscribing the spaces between several of the vanes. On the opposite side of the compressor is a discharge port 26 circumscribing an arc somewhat less than the distance between the two vanes and adjacent the 60 opposite end of the arc of expulsion. The space between the rotor and stator on opposite sides of the diametrical line which passes through the middle of the arc of expulsion defines respectively suction and compression chambers. Figure 2 65 shows a secondary suction port which will be referred to later.

In that form of the invention illustrated in Figures 1 and 2, the cylindrical portion of the casing is jacketed as indicated at 28 over that 70 area which circumscribes the compression chamber, the cooling medium being preferably oil which is admitted by way of the pipe 29 and exited through a discharge conduit 30. This oil has already come through the interior parts of 75

the compressor as will be later explained and is in general warmer than the fluid admitted to the compressor on the suction side although its temperature is cooler than the compressed fluid. 5 Therefore, while the oil is useful in cooling the compression chamber, it is in general preferable to restrict it in such manner that it shall not raise the temperature of the inducted fluid.

In the compressor of the type illustrated the 10 leakage which reduces the volumetric efficiency generally occurs at four places, between the rotor and stator in the arc of expulsion, around the ends of the rotor and vanes, between the ends of the vanes and the inner peripheral wall of the 15 cylinder, and about the vanes in their guideways. Various means have been devised for sealing these points of leakage, and the present invention offers nothing new with respect to sealing the joint along the expulsion arc. However, the invention 20 does propose an improved and very versatile means for sealing the compressor against leakage around the sides of the vanes, over the tops of the vanes and back of the vanes by impressing upon the sealing instrumentalities predominant 25 pressures derived from pressures within the compressor itself.

In my application for patent of which the present is a continuing application, is disclosed a sealing ring forming an end wall for the compression and suction chambers and a piston on the outside of said sealing ring and co-extensive with the area thereof with means for applying the high pressure of the compressor discharge to the rear of this piston for biasing the sealing 35 ring in opposition to the pressures within the suction and compression chambers.

In practice it was found that this sealing pressure was ordinarily so excessive as to produce unnecessary friction stresses between the ends of the rotor and vanes and the sealing ring which made it difficult to rotate the rotor and furthermore led to rapid wear of the engaging parts. 40

The invention as embodied in the present continuing application includes the sealing ring 31 seated in a suitable recess in the head and having 5 its outer peripheral edge co-incident with the inner peripheral cylindrical wall of the casing. The width of the sealing ring is such that it extends substantially to the bases of the vanes 10. 50 The sealing ring 31 rests against the sides of the vanes and the intervening portions of the rotor. It is normally, in the initial state of repose of the compressor, kept thus pressed by a plurality of small springs 32 seated in recesses 33 in the head 4 and pressing outwardly against said ring. These springs are of course totally inadequate 55 to maintain a sealing pressure after the pressures within the compressor build up, but they merely prevent leakage when the compressor first starts and when there is very little differential between inside and outside pressures.

In order to avoid the excessive endwise thrust against the rotating parts of the compressor which the imposition of discharged pressure over 65 the whole outer face of the sealing ring engenders and as covered in the parent application, the present invention contemplates in its broadest aspect segregating the portions of the area of the outer side of the sealing ring which lie opposite the compression and suction chambers, and applying to those segregate areas pressures from 70 within the compressor proportional to the pressures to be sealed in. For example, high discharge pressure would be imposed upon that part 75 of the ring opposite the compression chamber, and

suction pressure against that part of the ring which overlies the suction chamber, it being understood of course that the outside area of the sealing ring is at all times greater than the inside surface of said ring pressed upon by the 5 within pressures since part of the inside area of the ring is occluded by the sides of the vanes and by the intervening end portions of the rotor. It is also to be understood that the areas of the outer surface of the ring respectively impressed with 10 the discharge pressure and the suction pressure are always in excess of the pressures to be sealed and it is therefore quite feasible to use a lower pressure value on the outside of said ring to seal a higher pressure within. 15

A third pressure is available within the compressor. A certain amount of internal leakage is inevitable from the high to the low side of the compressor around one or another of the relatively moving parts so that in the oil spaces with 20 in the central portion of the compressor there is a pressure value which is a mean between the high pressure of the compression chamber and the low pressure of the suction chamber.

In the preferred embodiment of my invention 25 this intermediate pressure may be employed.

In order to segregate the high and low pressure areas on the outside of the sealing ring, the adjacent head 4 is provided with recesses 34 of more or less crescent shape corresponding to the shapes 30 of the chambers opposite which they lie, the cusps 36 and 37 of said recesses being adjacent the arc of expulsion. Since it will in general be necessary to seal the joint along said arc of expulsion against leakage a third recess 38 is provided at 35 this point. Pistons are arranged in said recesses. The pistons may be of any suitable construction, but in the present embodiment of the invention they consist of flexible cupped rubber members 39, 40 and 41 having side flanges 42 and 43 terminating in feather edges 44. Figure 11 shows that in their unconfined state, the flanges of the cupped members flare slightly and the bottom 45 bulges slightly outward. Said cupped members are crowded into the respective recesses in 45 inverted position in the manner indicated in the lower half of Figure 11 so that there is an inherent pressure of the flanges 43 against the corresponding walls of the recesses. The spaces enclosed beneath the cupped members or pistons 50 39, 40 and 41 form pressure chambers adapted to be placed in communication by suitable conduits with sources of compression within the compressor. When the pistons 39, 40 and 41 are in place, the slightly bulged bottoms of said pistons 55 press against corresponding areas of the sealing ring.

Figure 5 shows that the discharge port 26 is connected by a system of conduits 46 suitably bored through the casing to the pressure chamber back of the piston 39. Instead of making use of the suction pressure to activate the piston 40 which presses that part of the sealing ring opposite the suction chamber, the intermediate pressure is employed and consequently Figure 5 60 does not show the suction port communicating with the pressure chamber behind the piston 40. By reference to Figure 1 however, it will be observed that the space 16 between the trunnion and rotor and in which this intermediate pressure 65 builds up, is connected by conduits 47, 48 and 49 with the pressure chamber back of the piston 40. The piston 41 which overlies that part of the ring opposite the joint along the expulsion arc is actuated in response to the intermediate pressure de- 70 75

rived from one of the oil passages 50 by way of a conduit 51 best shown in Figure 6.

If it were desired to use the suction pressure instead of the intermediate pressure to seal the 5 suction chamber, the latter chamber would be tapped into the back of the piston 40, in a similar manner to that illustrated in connection with the leading of the discharge pressure to the back of the piston 39.

10 It has been stated that initial sealing contact between the sealing ring and the sides of the vanes and rotor is normally accomplished by means of the springs 32. As an alternative or 15 auxiliary to the springs 32, fluid pressure means may be employed for maintaining this initial sealing relationship of the parts. With this object in view, the suction port is tapped by means of a conduit 52 leading to the back of that 20 part of the sealing area not contacted by the pistons 39, 40 and 41. When the compressor first starts, the pressure behind the several pistons is nil or at least not greater than the pressures within the compressor. The area subjected to 25 these pressures is however temporarily augmented by pressure from the suction port being applied as indicated to the area of the sealing ring not affected by the pistons. Thus the entire outside area of the sealing ring is pressed by a pressure which may be not in excess of the pressure within the compressor, nevertheless, since 30 the outside area is greater than the inside area, the aggregate area on the outside exceeds that on the inside of the compressor and the sealing ring is initially biased in a sealing direction. 35 Figure 5 shows the conduit 52 controlled by an adjustable needle valve 53 which is not intended to be frequently adjusted, but merely once for all, according to the amount of auxiliary pressure which may be required in addition to the springs 40 32 or in the absence of such springs according to the amount of pressure necessitated to effect the proper initial sealing of the sealing ring.

The provision of the localized areas of differential pressure on the outside of the sealing ring, 45 and the pistons by means of which this differential pressure is applied, constitutes an extremely versatile arrangement permitting the said localized areas to be modified or shifted in designing various compressors, according to their 50 size, the speed at which they are to be operated and the pressures which they are called upon to produce. For example, it has been found, particularly with large sized compressors, that the angular velocity of the tips of the vanes gives 55 rise to a condition of destructive friction when the sides of the tips of the vanes are excessively pressed particularly when the compressor is compressing to high pressures. In designing such compressors, it becomes necessary merely to 60 move the localized areas away from the peripheral region of said vanes, while still maintaining an extent of their area which insures that a predominant pressure will be applied to the outer side of the sealing ring. The tips of the vanes 65 are thus relieved from excess pressures while at the same time the necessary sealing pressures are maintained.

It will be understood with reference to this 70 phase of the invention that while the sealing means above described may be applied separately to both sides of the compressor, it is deemed necessary in general only to apply the sealing ring to one side, since the pressure of the pistons against said sealing ring is transmitted to the 75 rotor and vanes, pushing them bodily over into

contact with the machined surface of the opposite head.

Leakage from the chambers of the compressor around the peripheral faces of the sealing ring 51 is prevented by means of continuous flexible 5 piston packings 54 and 55 seated in inverted portion in channels 56 and 57 formed in the said peripheral walls of said sealing ring. The faces of said pistons make contact with the adjacent side walls of the recesses in said head in which 10 said piston packings are mounted. The spaces enclosed behind said piston packings are placed in communication with suitable sources of pressure from within the compressor. Since the joints which these piston packings seal are fixed except 15 for a very slight range of sliding movement in a direction parallel to the axis of the rotor, the problem of nicely regulating the sealing pressure to prevent undue frictional wear or resistance is lacking. However it is a step in the nature of 20 good engineering to employ a sealing pressure which is not grossly in excess of the sealing needs. Therefore, while it is quite within the range of the invention to utilize the discharge pressure of 25 the compressor for projecting these piston packings against the walls with which they react, it is preferred to employ the intermediate pressure from the interior of the compressor between the suction and compression chambers. This is accomplished by providing grooves 58 and 59 in 30 the outer face of the sealing ring, the groove 58, shown in Figure 1, being in communication with oil conduits 60 extending transversely through the rotor and the contents of which conduits are under the desired intermediate pressure through 35 various minute leakage sources between the compression chamber and the suction chamber of the compressor, while the groove 59 derives its pressure from the interior displacement space on the discharge side.

40 The grooves 58 are shown in duplicate and spaced apart a distance equal at least to the width of one of the vanes, for the simple reason that since they are shown as being radially directed, they are occluded by each vane in the 45 course of its rotation. If there were only one groove 58 there would be a periodic cutting off of the pressure from the piston packing 55. Since the two grooves are spaced apart a distance equal at least to the width of the vanes both can never 50 be occluded at the same time and consequently the pressure behind the piston packing 55 is uninterrupted.

Referring now to Figures 2, 3 and 4, and Figures 12, 19 and 20 showing details, attention is 55 directed to the means for preventing the short circuiting of the compression pressure around the vanes. Figures 2, 3 and 4 show that the vanes 10 are each provided with a shoe 21 at its lower end and a shoe piece 23 at its upper end, the 60 shoes and shoe pieces being oscillatably seated in concave cylindrical seats in the ends of said vanes. The shoes 21 which bear against the split ring 17 merely act as wear pieces and to keep the entire ends of the vanes in contact with the split 65 ring instead of a mere line of contact as would normally be the case due to the canting of the vanes relative to the split ring on account of the eccentricity of the rotor relative to the trunnions. Wear between the inner ends of the vanes and 70 the split ring is thus distributed over the whole area of the shoe instead of being concentrated along a mere line of contact. The shoes 21 are not particularly concerned with sealing with the adjacent parts against pressure leakage for this 75

is taken care of in connection with the packing of the vanes and the upper shoe pieces.

Figure 12 shows that the rotor is provided both in front of and rearwardly thereof with reference to its direction of rotation with channels 61 and 62 in which are seated wear pieces 63 and 64 extending widthwise the full length of the rotor and flush with the rotor and vanes, said wear pieces being packed by flexible pistons 65 and 66 hermetically fitting the channels in which they lie and being in general of the same construction as the flexible pistons 39, 40 and 41 and the piston packings 54 and 55. The spaces enclosed within said channels by the respective pistons 15 form pressure chambers, the chamber on the advance side of the vane being in communication with the compression chamber by means of a bore 67 while the chamber on the trailing side of the vane is in communication 20 by way of a bore 64' with the space in the rotor back of the vane 10 which space is under the intermediate pressure of the compressor said pressure being transmitted through the ends of the vane slots which open as shown in Figure 2 25 into a space in the middle of the end plate, which space receives inevitable pressure leakage from both the compression and suction chambers and is also subject to the pressure of the lubrication system. Thus each side of the vane is 30 sealed against leakage by a pressure superior to that which it opposes.

Figure 12 shows also that the shoe piece 23 is biased actively outward against the inner peripheral wall of the casing of the stator by a wear piece 68 positioned at the open end of a channel 69 formed in the vane beneath said shoe piece, and backed by a flexible piston 70 subject to pressure within the chamber 71 derived by way of the conduit 72 from the high compression side 40 of the vane 10.

The shoe piece 23 shown in Figure 12 and illustrated in the preferred embodiment of the invention is symmetrical in cross section. A modified form of the invention is shown in Figures 19 and 20 in which the shoe is of asymmetrical cross section, the predominant portion 73 of which extends into the high compression chamber and presenting a broad ledge or shoulder 74 to the pressure in said chamber through which medium it is canted into firm frictional contact with the inner peripheral wall of the casing. The shoe in this form of the invention is shown as provided with a separable and therefore replaceable wear piece 75 grooved as at 76 to receive any suitable form of packing strips 77.

In this form of the invention the shoe piece is provided with a cylindrical channel 78 having a cross section greater than a semi-circle, and receives a correspondingly shaped bead 79 formed on the end of the vane, said shoe being irremovable radially, but readily removable for replacement by sliding it in a transverse direction after the rotor has been removed from the casing. The joint between the shoe and the end of the vane 65 is packed in a manner similar with that shown in connection with the form of the invention exemplified in Figure 12, a wear piece 80 being provided in a channel 81 formed in the shoe, said wear piece abutting the surface of the bead 79 and being backed by a flexible piston 82 in communication with the pressure of the compression chamber by way of a bore 83.

In connection with the packings on the advance and trailing sides of the vanes and in association with the joints between the outer shoe

pieces and the vanes, light sinuous springs 84 are placed behind the flexible pistons to impart initial sealing pressure to said pistons before the compressor upon starting has had the opportunity to generate the normal effective pressures. 5

It will be understood, in contemplating the operation of the compressor that all of the interstices between the various parts excluding of course the suction and compression chambers are filled with oil and that the fluid pressure impressed upon the various pistons is transmitted by the medium of oil. This oil is circulated by a pump 85 to the jacket 28, see Figure 13. From the jacket it flows to a suitable cooler 86 from which it is conducted by a conduit 87 to an oil chamber 88 adjacent the bearing on one side, see Figure 1, from which it flows through the bearing and through a series of conduits 60 in the rotor, through a series of oil passages 50 in the boss 89 of the head 4 which supports the trunnion 13, 20 through the opposite bearing and again to the pump by way of a passage 90.

A certain amount of oil necessarily finds its way into the suction or compression chambers mixing with the fluid to be compressed, the oil 25 and compressed fluid being conducted to a separator 91, see again Figure 13, and in the case of a refrigeration system the refrigerant being circulated through a condenser 92 and evaporator 93 and back to the induction side of the compressor. The separated oil is led back by way of a conduit 94 to the pump.

In certain fields of utility as for example, in refrigeration systems, it is sometimes desirable to draw two distinct suction pressures by one 35 end of the same compressor. This may be accomplished in the present invention by providing the primary and secondary suction or induction ports 24 and 27 respectively. The primary suction port communicates with the suction chamber 40 at the advance end thereof and therefore pulls the lowest pressure. By the time the suction chamber has rotated to the point at which it communicates with the secondary induction portion it is already occupied with fluid taken 45 in at the primary induction portion so that it is capable of drawing upon the secondary induction port with a higher pressure value. The primary induction port may lead from a coil at a low ice making temperature 15° F., while the secondary induction port may lead from a coil at a higher temperature such for example as is suitable for keeping an ice storage room at or just before freezing, 28°-32° F.

Referring now to that form of the invention 55 illustrated in Figures 14, 15 and 16, a compressor of the gear type is illustrated, the rotor comprising two meshing gear impellers operating within a chamber formed by a casing having a cylindrical peripheral portion 97 and closed by heads 98 60 and 99. The problem of sealing insofar as it is generic to this form of the invention and previously described is confined to the end seal 100 shown at the left of the rotor elements in Figure 14 and which is similar in construction and in mode of operation to the first described form of the invention excepting of course that its shape is modified in accordance with the shape of the rotor chamber, the sealing ring being illustrated in Figure 16 and being in the form of a figure 70 8. The head 98 between which and the rotor elements the sealing ring 100 is placed is provided with suitably located recesses in which the flexible cupped pistons 101 and 102 are seated. The piston 101 follows the general contour of the 75

compression chamber between the gears while the piston 102 is much larger, following the shape of the suction and transfer chambers of the compressor. In position, extent and construction, 5 these pistons follow the same principles as do corresponding parts of that form of the invention shown in Figures 1 and 2. Figure 14 shows that the piston 101 which seals the compression chamber derives its opposing pressure from the 10 discharge chamber of the compressor while the piston 102 is in communication with suction pressure derived from the interior of the compressor through a conduit 103. The peripheral edges of the sealing ring 100 are provided with channels 15 and endless piston packings seated therein in the same manner as is illustrated in connection with the preferred form of the invention. Figure 16 shows that these peripheral packing pistons receive their operating pressure by way of grooves 20 104 formed on that face of the sealing ring which is adjacent the interior of the compressor.

It will be understood that the specific means 25 for sealing against the various phases of leakage as described and illustrated in the foregoing disclosure are merely illustrative and by no means to be construed as limiting the scope of the invention, which includes broadly all novel equivalent constructions for accomplishing the new and 30 advantageous results as herein set forth.

30 What I claim is:

1. Rotary compressor comprising a casing, a rotor within said casing, said rotor co-operating with the inner peripheral wall of said casing and with suitable end wall structure to form suction 35 and compression chambers, including a sealing member forming an end wall for at least one side of said suction and compression chambers making endwise contact with said rotor whereby the area of said end wall exposed to pressure within said chambers is less than the entire area of the outer side of said end wall, means for pressing said end wall against said rotor by externally applied fluid pressures derived from pressures within said compressor, and means for restricting the application 40 of said derived pressures to areas on the outer side of said end wall remote from the outer peripheral portion thereof for relieving the peripheral portions of the rotor, that is to say, those parts having maximum angular velocity, from excess endwise friction, said restricting means comprising a head between which and the side of the rotor said end wall is positioned, said head having recesses opening in the face thereof, the open sides of 45 which delineate the said areas, flexible cupped members hermetically fitting said recesses and forming therewith pressure chambers, the bottoms of said cupped members contacting said end wall and the derived pressures being in communication with said pressure chambers, the extent 50 of said areas being sufficiently less than the entire area of the outer side of said end wall to avoid excessive sealing pressure but sufficiently great to oppose a predominant pressure to the pressure within said chambers.

2. Rotary compressor comprising a casing, a rotor within said casing and eccentrically mounted with respect to the interior peripheral wall of said casing so as to contact the latter through an appreciable arc, vanes slidably guided by said rotor engaging the peripheral wall of said casing and terminating flush with the ends of said rotor, said rotor, vanes, the inner peripheral wall of said casing and suitable end wall structure co-operating 70 to form suction and compression chambers

on opposite sides of said arc, including a sealing member forming an end wall for at least one side of said suction and compression chambers making endwise contact with said rotor and said vanes whereby the area of said end wall exposed to 5 pressure within said chambers is less than the entire area of the outer side of said end wall, means for pressing said end wall against said rotor and said vanes by externally applied fluid pressure derived from pressures within said compressor, and 10 means for restricting the application of said derived pressures to areas on the outer side of said end wall remote from the outer peripheral portion thereof for relieving the peripheral portions of said vanes, that is to say, those parts having 15 maximum angular velocity from excess endwise friction, said restricting means comprising a head between which and the side of the rotor said end wall is positioned, said head having recesses opening in the face thereof, opposite the chambers 20 to be sealed, the open sides of which delineate the said areas, flexible cupped members hermetically fitting said recesses and forming therewith pressure chambers, the bottoms of said cupped members contacting said end wall and the derived 25 pressures being in communication with said pressure chambers, the extent of said areas being sufficiently less than the entire area of the outer side of said end wall to avoid excessive sealing pressure, but sufficiently great to oppose predominant 30 pressures to the pressures within said chambers.

3. Rotary compressor comprising a casing, a rotor within said casing eccentrically mounted 35 with respect to the interior peripheral wall of said casing so as to contact the latter throughout an appreciable arc, vanes slidably guided by said rotor engaging the inner peripheral wall of said casing, said vanes, rotor, the inner peripheral wall of said casing combining with suitable end wall 40 structure to form suction and compression chambers, on opposite sides of said arc, including a sealing member forming an end wall for at least one side of said suction and compression chambers making endwise contact with said rotor and said vanes whereby the area of said end wall exposed to 45 pressure within said chambers is less than the entire areas of the outer side of said end wall, means for pressing said end wall against said vanes and rotor by externally applied fluid pressures derived from pressures within said compressor at values proportional to the pressures to be sealed, and means for restricting the application of said derived pressures to areas on the outer side of said end wall remote from the outer peripheral portion thereof for relieving the peripheral portions of the vanes, that is to say, those parts having maximum angular velocity, from excess endwise friction, said restricting means comprising a head between which and the side of the 50 rotor and vanes said end wall is positioned, said head having recesses opening in the face thereof opposite the chambers to be sealed and opposite said arc of contact, the open sides of which recesses delineate the said areas, flexible cupped members hermetically fitting said recesses and forming therewith pressure chambers, the bottoms of said cupped members contacting said end wall and the derived pressure being in communication with said pressure chambers, the extent 55 of said areas being sufficiently less than the entire area of the outer side of said end wall to avoid excessive sealing pressure, but sufficiently great to oppose predominant pressures to the pressures within said chambers.

4. Rotary compressor as claimed in claim 3, the cupped member opposite said arc of contact deriving its pressure from leakage pressure between the compression and suction chambers in the interior of said compressor.

5. Rotary compressor comprising a casing, including a head, a rotor within said casing, said rotor co-operating with the inner peripheral wall of said casing and with said head to form suction and compression chambers, including a sealing member forming an end wall for at least one side of said suction and compression chambers, fitting within the chamber of said casing against the inner peripheral wall of said casing on the one hand and upon a portion of said head on the other, said end wall making endwise contact with said rotor whereby the area of said end wall exposed to pressures within said chambers is less than the entire area of the outer side of said end wall, the edges of said end wall which abut the peripheral wall of said casing and said rotor being formed with channels, endless flexible channeled members seating within the channels of said end wall with their flanges in hermetic relation to the sides of said channels and their bottoms engaging respectively the inner peripheral wall of said casing and said head, the channels in said end wall and said flexible members forming pressure chambers communicating with sources of pressure within said compressor, means for pressing said end wall against said rotor by externally applied fluid pressures derived from pressures within said compressor, and means for restricting the application of said derived pressures to localized areas on the outer side of said end wall, recesses in said head opening in the face thereof, pistons hermetically fitting said recesses and forming therewith pressure chambers, the bottoms of said pistons contacting said end wall in surfaces defining said areas and the derived pressures being in communication with said pressure chambers, the extent of said areas being sufficiently less than the entire area of the outer side of said end wall to avoid excessive sealing pressure, but sufficiently great to oppose predominant pressures to the pressures within said chambers.

6. Rotary compressor comprising a casing, a rotor within said casing, said rotor co-operating with the inner peripheral wall of said casing and with suitable end wall structure to form suction and compression chambers, including a sealing member forming an end wall for at least one side of said suction and compression chambers making endwise contact with said rotor whereby the area of said end wall exposed to pressure within said chambers is less than the entire area of the outer side of said end wall, means for pressing said end wall against said rotor by externally applied fluid pressures derived from pressures within said compressor having values proportional to the pressures to be opposed, means for restricting the application of said derived pressures to areas on the outer side of said end wall opposite the respective chambers to be sealed, remote from the outer peripheral portion thereof for relieving the peripheral portions of the rotor, that is to say, those parts having maximum angular velocity, from excess endwise friction, the extent of said areas being sufficiently less than the entire area of the outer side of said end wall to avoid excessive sealing pressure, but sufficiently great to oppose a predominant pressure to the pressures within said chambers, and means for imparting an initial sealing bias to said end wall comprising a conduit leading from a source of pressure within said compressor to the outer side of said end wall outside of said restricted areas.

7. Rotary compressor comprising a casing, a rotor within said casing and eccentrically mounted with respect to the interior peripheral wall of said casing so as to contact the latter through an appreciable arc, vanes slidably guided by said rotor engaging the peripheral wall of said casing and terminating flush with the ends of said rotor, said rotor, vanes, the inner peripheral wall of said casing and suitable end wall structure co-operating to form suction and compression chambers on opposite sides of said arc, including a sealing member forming an end wall for at least one side of said suction and compression chambers making endwise contact with said rotor and said vanes whereby the area of said end wall exposed to pressure within said chambers is less than the entire area of the outer side of said end wall, means for passing said end wall against said rotor and vanes by externally applied fluid pressure derived from pressures within said compressor, means for restricting the application of said derived pressures to areas on the outer side of said end wall remote from the outer peripheral portion thereof for relieving the peripheral portions of said vanes, that is to say, those parts having maximum angular velocity from excess endwise friction, said restricting means comprising a head between which and the side of the rotor said end wall is positioned, said head having recesses opening in the face thereof, opposite the chambers to be sealed, the open sides of which delineate the said areas, flexible cupped members hermetically fitting said recesses and forming therewith pressure chambers, the bottoms of said cupped members contacting said end wall and the derived pressures being in communication with said pressure chambers, the extent of said areas being sufficiently less than the entire area of the outer side of said end wall to avoid excessive sealing pressure, but sufficiently great to oppose predominant pressures to the pressures within said chambers, and means for imparting an initial sealing bias to said end wall comprising a conduit leading from a source of pressure within said compressor to the outer side of said end wall outside of said restricted areas.

8. Rotary compressor comprising a casing, a rotor within said casing, said rotor co-operating with the inner peripheral wall of said casing and with suitable end wall structure to form suction and compression chambers, including a sealing member forming an end wall for at least one side of said suction and compression chambers making endwise contact with said rotor whereby the area of said end wall exposed to pressure within said chambers is less than the entire area of the outer side of said end wall, means for pressing said end wall against said rotor by externally applied fluid pressures derived from pressures within said compressor, and means for restricting the application of said derived pressures to localized areas on the outer side of said end wall, said means comprising a head between which and the side of the rotor said end wall is positioned, said head having recesses opening in the face thereof, pistons hermetically fitting said recesses, the bottoms of said pistons contacting said end wall on surfaces which delineate said areas, being biased thereagainst by said derived pressures, the extent of said areas being sufficiently less than the entire area of the entire outer wall to avoid excessive sealing pressure but sufficiently great

to oppose predominant pressure to the pressure within said chambers.

9. In combination with a rotary compressor comprising a casing and a rotor therein, defining 5 between them a chamber, the rotor being eccentrically mounted on a shaft coaxial with the circumferential wall of said casing, said rotor being formed with radial guideways, and sliding vanes in said guideways projectable into said chamber 10 and bearing against the peripheral wall of said casing, means for sealing said vanes against pressure leakage between themselves and said guideways, comprising a channel opening in the joint between said vanes and guideways, a sealing 15 element in said channel to close said joint, and means for placing the space within said channel behind said sealing element in communication with said chamber.

10. In combination with a rotary compressor, 20 comprising a casing and a rotor therein, defining between them a chamber, the rotor being eccentrically mounted on a shaft coaxial with the circumferential wall of said casing, said rotor being formed with radial guideways, and sliding vanes in said guideways projectable into said chamber and bearing against the peripheral wall of said chamber, said vanes separating said chamber into parts having differential pressures on 25 opposite sides of said vanes, means for admitting fluid under dominant pressure derived from the discharge pressure of the compressor to the inner ends of the guideways behind said vanes, said rotor being formed with channels opening in the joints between each vane and its guideway on 30 opposite sides of the said vanes, packing members in said channels extending through the width of said vanes and bearing against said vanes to close said joints, means for placing the space within the channel behind the packing on the advance 35 side of said vane into communication with the part of the first named chamber in advance of said vanes, and means for placing the space within the channel behind the packing on the trailing side of said vane into communication with fluid 40 under pressure behind said vanes.

11. Rotary compressor comprising a casing, a rotor within said casing, said rotor cooperating with the inner peripheral wall of said casing and with suitable end wall structure to form suction 45 and compression chambers, including a sealing member forming an end wall for at least one side of said suction and compression chambers, making an endwise contact with said rotor whereby the area of said end wall exposed to pressure 50 within said chambers is less than the entire area of the outer side of the said end wall, means for pressing said end wall against said rotor by externally applied fluid pressures derived from pressures within said compressor, said pressure applying 55 means having an area of contact with the outer face of said end wall substantially coincident with the areas of the inner face of said end wall exposed to the internal pressure of said compressor.

12. Rotary compressor comprising a casing, a rotor within said casing, said rotor cooperating with the inner peripheral wall of said casing and with suitable end wall structure to form suction 60 and compression chambers, including a sealing member forming an end wall for at least one side of said suction and compression chambers making endwise contact with said rotor whereby the area of said end wall exposed to pressure within 65 said chambers is less than the entire area of the outer side of said end wall, means for pressing 70

said end wall against said rotor by externally applied fluid pressures derived from pressures within said compressor, said pressure applying means having an area of contact with the outer face of said end wall substantially coincident with the area of the inner face of said end wall exposed to the internal pressure of said compressor, the extent of said areas to which pressure is applied being sufficiently less than the entire area of the outer side of said end wall to avoid excessive sealing pressure but sufficiently great to oppose a predominant pressure to the pressures within said chambers.

13. In a compressor including a casing and a rotor within the casing, a sealing ring within 15 the casing abutting an end of the rotor and forming an end wall of the compression and suction chambers of the compressor, said ring having a peripheral channel, a sealing piston seated in said channel forming a movable wall of the 20 pressure chambers defined by the walls of said channel and the said sealing piston, co-acting with the peripheral wall of said casing, said pressure chamber being in communication with an internal pressure of the compressor.

14. In a compressor including a casing and a rotor within the casing, a sealing ring within 25 the casing abutting an end of the rotor and forming the end wall of the compression and suction chambers of the compressor, the outer peripheral face of said ring cooperating sealingly with the peripheral wall of said casing, said ring having an inner peripheral face adapted to co-act with the outer surface of a boss extending inwardly from said casing, said inner and outer 30 peripheral faces being formed with channels, sealing pistons seated in said channels forming movable walls of the pressure chambers defined between the walls of said channels and said sealing pistons, said pistons co-acting respectively 35 with the peripheral wall of said casing and the outer surface of said boss, said pressure chambers being in communication with an internal pressure of the compressor.

15. In a compressor including a casing and a 45 rotor within the casing, a sealing ring within said casing abutting an end of the rotor and forming the end wall of the compression and suction chambers of the compressor, the outer peripheral face of said ring cooperating sealingly 50 with the peripheral wall of said casing, said ring having an inner peripheral face adapted to co-act with the outer surface of a boss extending inwardly from said casing, said inner and outer 55 peripheral faces being formed with channels, sealing pistons seated in said channels forming movable walls of the pressure chambers defined between the walls of said channels and said sealing pistons, said pistons co-acting respectively 60 with the peripheral wall of said casing and the outer surface of said boss, said pressure chambers being in communication with sources of pressures within the compressor proportional to the pressures against which they are opposed.

16. Rotary compressor comprising a casing, a 65 rotor therein, said rotor cooperating with the inner peripheral wall of said casing and with suitable end wall structure to form suction and compression chambers, including a sealing ring 70 forming an end wall for at least one side of said suction and compression chambers, making endwise contact with said rotor, means for pressing said end wall against said rotor by fluid pressures derived from pressures within said compressor and having values proportional to the 75

pressures to be opposed, the said means restricting said pressures to segregated areas of said wall, said sealing ring having a peripheral channel, a sealing piston seated in said channel forming a movable wall of the pressure chamber defined by the walls of said channel and said sealing piston, said sealing piston co-acting with the peripheral wall of said casing, said pressure chamber being in communication with an internal pressure of the compressor.

17. Rotary compressor comprising a casing, a rotor within said casing, said rotor cooperating with the inner peripheral wall of said casing and with suitable end wall structure including a head of the casing, to form suction and compression chambers, including a sealing member forming an end wall for at least one side of said suction and compression chambers, making endwise contact with said rotor whereby the area of said end wall exposed to pressure within said chambers is

less than the entire area of the outer side of said end wall, means between said head and end wall for pressing the latter against said rotor by externally applied fluid pressures, derived from pressures within said compressor, said means being constructed to restrict the application of said derived pressures to localized areas on the outer side of said end wall, said means comprising pistons hermetically fitting recesses formed in the head or sealing ring, the bottoms of said pistons occluding the open sides of said recesses and contacting the surfaces of the adjacent member which delineate the said localized areas, being biased thereagainst by said derived pressures, the extent of said areas being sufficiently less than the entire area of the entire outer wall of said sealing means to avoid excessive sealing pressure, but being sufficiently great to oppose predominant pressure to the pressure within said chambers.
